(No Model.)

G. A. TOWER.
ELECTRIC RAILWAY SIGNAL.

No. 426,222.

Patented Apr. 22, 1890.

UNITED STATES PATENT OFFICE.

GEORGE ARMES TOWER, OF RICHMOND, VIRGINIA.

ELECTRIC RAILWAY-SIGNAL.

SPECIFICATION forming part of Letters Patent No. 426,222, dated April 22, 1890.

Application filed June 14, 1889. Serial No. 314,234. (No model.)

To all whom it may concern:

Be it known that I, GEORGE ARMES TOWER, a citizen of the United States, residing at Richmond, in the county of Henrico and State of Virginia, have invented a new and useful Electric Railway-Signal, of which the following is a specification.

The invention relates to improvements in electric railway-signals.

10 The object of the present invention is to produce a signal which will indicate to trains the presence of approaching trains by blowing the whistle of an engine, which blowing will continue until stopped by the engineers 15 of the warned trains.

The invention consists in the construction and novel combination and arrangement of parts hereinafter fully described, illustrated in the accompanying drawings, and pointed 20 out in the claims hereto appended.

In the drawings, Figure 1 is a plan view showing the improved apparatus applied to a railway-track. Fig. 2 is a perspective view, partly in section, of the signal-operating device. Fig. 3 is a side elevation of the signal-sounding mechanism, and Fig. 4 is a detail view of the slide that carries the soft-iron cores.

Referring to the accompanying drawings, A designates an L-shaped plate, which is secured to the side of the cow-catcher, which side may be either the right or the left hand side; but the position must be the same on all engines, and the said plate A has its horizontal arm provided with a spring-actuated 30 rod B, sliding in keepers a and a' . The front end of the rod B has an eye b, to which is attached a cord C, that passes around a guide-pulley C', and is designed to be connected to the lever which operates the whistle, whereby 35 when the rod B, which is normally locked against movement, is released the cord C will be pulled and the whistle sounded. The rod B is provided intermediate of its ends with an annular flange b', against which bears a 40 spring D, which has its other end bearing against the keeper a. The rod is held against rearward movement and the spring D maintained compressed by a locking-bolt E, which is provided along its edges with lateral flanges 45 e, that slide in suitable ways a^2 , formed upon the plate A. The bolt is slotted near its lower end to provide an opening e', through which

passes the rod when the bolt is raised, and the rod remains in that position until withdrawn by the engineer, it being designed to have a 55 cord C² extending from the cab and connected to the cord C for that purpose. The bolt E normally rests upon and is raised by a bar F, which has its upper portion f cylindrical and its lower portion f' squared, and which slides 60 in keepers a^3 and a^4 , the former having a round opening to receive the cylindrical portion f, and the latter being provided with a square opening to receive the lower portion of the bolt.

Around the cylindrical portion f, and between the keepers a^3 and a^4 , is a spiral spring G, which bears against the upper keeper a^3 and the shoulder of the bar formed by the squared portion and holds the bar F normally depressed. The lower end f² is bifurcated and 70 is provided with a roller f³, which causes the bar F to pass easily up the inclined sides h of a hinged plate H. The plate H is hinged to the end of a metal box or casing I, and has pivoted to its free end a depending rod J, 75 which is provided with a shoulder j, that is designed to be engaged by a slide K to hold the said plate H firmly in its normal position and cause its inclined sides h to engage the bar F and blow the whistle. In order to keep 80 the depending rod J approximately vertical, it has pivoted to its lower end a horizontal rod J', which is pivoted to the side of the casing. The plate H is normally held elevated by a spring L, which is secured to the casing 85 I and bears against the under side of the plate H, and the said plate H may be depressed when the shoulder j is not engaged by the slide K to permit the bar F to pass without blowing the whistle. The slide K moves horizontally in suitable grooves in the casing I, and is provided with a longitudinal slot k, in which the vertical rod J works, and the said slide K has secured to its ends soft-iron cores 90 K', which are adapted to be attracted by helices M and M' to carry the slide into and out of engagement with the shoulder j of the vertical rod J. The wires m and m' leave the helices in opposite directions and are secured to the rail and bars N on the opposite side of 100 the track to which the casing is secured, whereby when a train passes the roller f³ will engage the bar N, close the circuit, and cause the slide to be drawn into or out of engage-

ment with the shoulder j , according as the train is approaching or receding from the plate H.

In practice the batteries C^3 will be arranged 5 within the casing I; but for convenience of illustration they are shown separate from the casing, and each of the pairs of wires m and m' has one wire attached to a rail and the other connected to a bar N, arranged beside the 10 track, whereby when an engine passes by the roller f^3 , should the same be on the proper side, will come in contact with the bar N and close the circuit, the engine itself being in contact with the rail to which one wire is connected. 15 The bar F and signal-sounding mechanism being arranged on one side of an engine—say the right-hand side—a train traveling in the direction of the arrow and approaching the bar N will on reaching the bar N close the 20 circuit and lock the plate H, and should another train be approaching in the direction opposite to that indicated by the arrow its signal-operating mechanism will come in contact with the locked plate H of the signal-operating mechanism, and the whistle will be 25 blown and the engineer will be warned.

What I claim is—

1. In a railway-signal, the combination of the plate A, the spring-actuated rod sliding 30 in suitable keepers of the plate and designed to be connected with the whistle of a locomotive, the locking-bolt sliding in suitable ways and provided with an opening and capable of movement to bring the opening opposite the 35 end of the bolt, and the bar arranged beneath the locking-bolt and operating the same, substantially as described.

2. The combination, in a railway-signal, of the L-shaped plate having the keepers a and 40 a' on one arm and the keepers a^3 and a^4 and the ways a^2 on the other arm, the spring-actuated rod arranged in the keepers a and a' , the locking-bolt sliding in the ways a^2 and

provided with an opening adapted to receive the rod, the bar arranged in the keepers a^3 45 and a^4 and provided with the roller f^3 , and the spring G, arranged between the keepers a^3 and a^4 and to hold the bar normally depressed, substantially as described.

3. In a railway-signal, the combination of 50 the casing, the hinged plate triangular in longitudinal section and provided with a depending rod, and a slide having at its ends soft-iron cores and adapted to be drawn into and out of engagement with said rod by helices 55 arranged at the ends of the slide, substantially as described.

4. In a railway-signal, the combination of the casing, the plate triangular in longitudinal section and hinged thereto, and having a depending rod provided with a shoulder, and the slide having the soft-iron cores and provided with a longitudinal slot to receive the depending rod, said slide being drawn into and out of engagement with the shoulder by 60 helices arranged at each end of the slide, substantially as described.

5. In a railway-signal, the combination of the casing, the hinged plate triangular in longitudinal section and provided with the depending rod J, the rod J' , pivoted to the casing and the end of the rod J, the spring L, holding the plate normally elevated, the slide provided with a central opening to receive the depending rod J and having at its ends soft-iron cores, and the helices arranged at each 75 end of the slide and adapted to draw the latter into and out of engagement with the rod J, substantially as described.

In testimony that I claim the foregoing as 80 my own I have hereto affixed my signature in presence of two witnesses.

GEORGE ARMES TOWER.
